PROCESS FOR THE QUANTITATIVE ESTIMATION OF VAPORS IN GASES.

1,272,922.

Specification of Letters Patent.

Patented July 16, 1918.

Application filed October 15, 1917. Serial No. 196,720.

To all whom it may concern:

Be it known that we, HAROLD SIMMONDS DAVIS, British citizen, residing at the city of Winnipeg, in the county of Selkirk and

5 Province of Manitoba, Canada, and MARY DAVIDSON DAVIS, British citizen, residing at the city of Winnipeg, in the county of Selkirk and Province of Manitoba, Canada, have jointly invented a certain new and useful Process for the Quantitative Estimation 10 of Vapors in Gases, of which the following is a specification.

This invention relates to the method for the quantitative estimation of vapors in 15 gases by the determination of their partial vapor pressures and has for its object to render a rapid and convenient method for the determination of such vapor pressures.

Our process is carried out in an apparatus 20 of the form illustrated in the accompanying drawing which represents a vertical section of the apparatus and in which:—

Two flasks 1, 2 of about 300 cc. capacity 25 are connected by a manometer tube 3, sealed into their necks. Into the neck of each flask is ground a glass stopper 4.4. Through each of the ground glass stoppers pass two tubes. One of these, 5.5, is closed at the upper end by a stopcock. Through the 30 other, 6.6, which terminates about 1 cm. above the stopper, a metal rod, 7.7, passes to the bottom of the flask projecting above the stopper to a distance of about 11 cm. The upper end of this rod is screwed into 35 a short piece of metal rod of larger diameter, 8.8. Over this larger piece of rod and extending down over the glass tubing projecting above the stopper is slipped a piece of tightly fitting rubber pressure tubing, 40 9.9. The rubber joints are made tight by means of vacuum grease and wire. 10.10, 10.10.

To the bottom of the metal rod a small 45 sealed glass bulb, 11.11, is attached by means of small supports and fine copper wire. This bulb, which has a thin bottom, contains sealed up within it some of the liquid whose vapor is to be determined in the gas in question. By pushing down the rod at the 50 proper time or by giving it a slight tap,

the bulb at the end can be broken, thus liberating the liquid it contains. The rubber tubing then draws the rod back into place.

The manometer tube may be filled with 55 mercury or any suitable liquid and any difference in pressure in the two flasks can be read directly on a glass scale 12. When mercury is used for the manometer liquid, 1 mm. is a convenient size for the bore of 60 the manometer tube.

It is not necessary that the tubes 5.5 pass through the stoppers, they may be attached to the necks of the flasks or any place where, 65 by opening the stopcocks, the pressures inside and outside the flasks can be equalized.

The actual dimensions of any of the parts of the apparatus can be varied within wide limits; but, as will be seen from what follows, in order to obtain accurate results 70 quickly, it is essential that when the bulb of liquid is broken in the bottom of the flask its vapor should quickly penetrate all the interior of the flask; hence, local pockets in the interior surface into which the vapor 75 would diffuse only slowly should be avoided and all connecting tubes should have a small volume compared with the total volume of the flask.

The theory of the method is based upon 80 the principle often called Dalton's law of partial pressures, according to which the vapor pressure from a liquid is independent of the kind of gas above it, provided the gas is inert. Suppose the two closed flasks 85 described above are filled with an inert gas at atmospheric pressure. If now a small sealed glass bulb containing a quantity of the same liquid is broken in each, the liquid will partially evaporate and will add its 90 vapor pressure to the pressure already existing in the flasks; and if the temperatures of the flasks remain the same, the same additional pressure will be developed in each so that the manometer connecting them will 95 record no difference in pressure. Even if the temperatures of the flasks do change no difference in pressure will be recorded until there is a relative difference in temperature between them.

Now suppose that one of the flasks had contained a certain pressure of vapor of the same composition as the liquid in the sealed bulb, and that this pressure was less than the saturation pressure at that temperature. When the small bulb of liquid was broken in this flask, the liquid would not add all its vapor pressure to the pressure already in the flask for part of that pressure was already due to its vapor. It could add only the pressure required to bring its vapor pressure up to saturation; and since the total saturation pressure was added to the inert gas in the other flask, the manometer connecting the two would register a pressure equal to the pressure of this particular vapor in the original gas.

Each of the sealed bulbs must contain considerably more liquid than it is required to saturate, at that temperature, the atmosphere in the flask into which it is broken with the vapor in question.

Two important points should be noticed here—The partial pressure of any particular vapor in a sample of gas is independent of the temperature of the gas, provided that the total pressure on the gas remains constant while the volume can change with the temperature and provided the vapor remains always unsaturated and obeys the simple gas laws.

Second. The difference in pressure developed between the two flasks, one of which contains inert gas and vapor and the other inert gas free from vapor, will vary as the absolute temperature, provided the relative temperatures of the flasks remain the same. That is, for practical purposes the difference in pressures is independent of the temperature.

An apparatus constructed on this principle will therefore measure a definite quantity, the pressure of any particular vapor in the gas at a definite gas pressure.

An actual determination of the pressure of a vapor in any particular gas is carried out in the following way—

One of the flasks is filled by displacement with the gas and the other with pure air containing none of the vapor. When the temperatures of the gases in the flasks have become the same, the stopcocks on both sides are opened to bring the gases to atmospheric pressure, after which they are closed. Next the small sealed glass bulbs containing liquid of the same composition as the vapor are broken by pushing on the metal rods and the apparatus is allowed to stand with occasional shaking until the manometer levels cease changing. In the case of the determination of the amount of benzene vapor in a gas the time required to reach equilibrium was 5-10 minutes for flasks of 140 cc.

capacity and 10-15 minutes for those of 340 cc. capacity.

65

If greater accuracy is required, the determination may be carried out with the apparatus submerged in a thermostat and correction should be made for the change in volume in the flasks due to the movement of the manometer liquid. For ordinary work this is quite unnecessary.

The differential pressure which develops between the two flasks is equal to the original partial pressure of the vapor in the gas, 75 when the total pressure on the gas is equal to the atmospheric pressure at the time of the experiment. This can be reduced to standard conditions in the following way.

Let P be the atmospheric pressure at the 80 time of the experiment.

Let P_o be normal atmospheric pressure == 76 cm. of mercury.

Let X be the differential pressure developed between the flasks.

85

Then

$$\frac{XP_o}{P}$$

is equal to the partial pressure of the vapor 90 in the gas when the total pressure on the gas is P_o . As was pointed out before, the value

$$\frac{XP_o}{P}$$

95

is independent of the temperature provided every component of the gas remains unsaturated.

In a similar way the total of the partial 100 pressures of two or more vapors may be reduced to its value for a total standard pressure on the gas.

However, though this partial pressure of a vapor is independent of the temperature, 105 the actual weight of the vapor contained in unit volume of the gas depends on the temperature. For one vapor this may be calculated from the partial pressure in the following way on the assumption that the vapor gives the same partial pressure as it would if it were a true gas at that temperature and molecular concentration:—If M is the gram molecular weight of the vapor, then the weight of the vapor in 1 liter of gas 115 at a temperature T (absolute) and normal pressure P_o is equal to

$$\frac{XP_o}{P} \frac{1}{P_o} \frac{M}{22.4} \frac{273}{T}$$

120

or

$$\frac{XM273}{P22.4T} \text{ grams.}$$

125

We claim:

The process for the quantitative estima-

tion of a vapor in a gas which consists in filling to the same pressure two similar flasks connected by a manometer, the one with the gas to be analyzed, the other with an inert gas free from the vapor in question and of breaking inside each flask a sealed glass bulb, which bulb contains a liquid of the same composition as the vapor to be estimated in a larger quantity than

that required to saturate with the vapor, at 10 that temperature, the flask in which it is broken, and of calculating the original concentration of the vapor in the gas from the differential pressure which develops between the two flasks.
